(57) **CLAIM**

The ornamental design for a pendant lamp, as shown and described.

DESCRIPTION

FIG. 1 is a front elevation view of a pendant lamp showing the new design in its first position;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is a front elevation view of the pendant lamp showing the new design in a second position;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is a first perspective view thereof;

FIG. 16 is a second perspective view thereof;

FIG. 17 is a front elevation view of the pendant lamp showing the new design in a third position;

FIG. 18 is a rear elevation view thereof;

FIG. 19 is a left side elevation view thereof;

FIG. 20 is a right side elevation view thereof;

FIG. 21 is a top plan view thereof;

FIG. 22 is a bottom plan view thereof;

FIG. 23 is a first perspective view thereof; and,

FIG. 24 is a second perspective view thereof.
